TONGUELESS TEARING STRIP CONTAINER

Thomas P. Keogh, New York, N. Y., assignor to
Continental Can Company, Inc., New York,
N. Y., a corporation of New York

Application June 6, 1945, Serial No. 597,865

1 Claim. (Cl. 220—54)

1

The invention relates to new and useful improvements in a sheet metal container and more particularly to a container which is scored along parallel lines to provide a tearing strip which may be removed when it is desired to open the container. It is customary to provide the blank from which the body wall of the container is formed with a projecting tongue in alignment with the scored portion which is to form the tearing strip so that a key may be placed on the tongue and by the turning of the key the tearing strip removed and thus the container opened.

An object of the present invention is to provide a container having a tearing strip which is tongueless, that is, the body wall is scored so that the end of the tearing strip to which the key is to be applied is a part of the body wall of the container and not a projecting portion of the body blank.

A further object of the invention is to provide a container of the above type with an inserted collar which is so shaped in the region of the tearing strip to permit the insertion of a tool through a formed opening in the body wall for breaking the body wall at the end of the tearing strip.

In the drawings,

Figure 1 is a view partly in side elevation and partly in section of a container embodying the improvements;

Figure 2 is a similar view of a portion of the body wall showing an opening formed in the body wall for the insertion of a tool used for rupturing the metal and forming a free end in the tearing strip on which a key may be placed for removing the tearing strip.

Figure 3 is a view similar to Figure 2 but showing the metal of the body wall ruptured and the freed end of the tearing strip lifted preparatory to the attachment of a key thereto.

Figure 4 is a view in side elevation of a key which may be used for rupturing the metal and lifting the freed end of the tearing strip and also for removing the tearing strip.

The container is preferably made of sheet metal and the body wall is formed from a blank the edges of which are joined in a side seam. The body wall is indicated at 1 in the drawings and the side seam is indicated at 2. As shown, the side seam is of the usual lock or lap type, although it will be understood that the invention is not limited to the character of the side seam and this side seam may be a lap seam throughout.

The body wall is preferably beaded inwardly,

as indicated at 3, and disposed within the container is a collar 4 which contacts with the bead 3 at the lower end thereof. Attached to the body wall is an end closure 5 which is secured to the body wall by a double seam 6. These parts are all of the usual construction and further description of the container as a whole is not thought necessary.

The blank which forms the body of the container is scored along parallel lines 7, 7. These score lines preferably extend from one end of the blank to the other and in the finished can completely encircle the body. The body wall is also scored along the line 8 which extends from one score line to the other. The body wall is further scored as indicated at 9. This score line 9 is circular and sets off a portion of the body wall which may be readily ruptured by pressure applied to the outer face of the can body so as to provide a hole through the body wall when it is desired to open the container.

When the body wall is ruptured along the score line 9 an opening 10 is formed. The score line 8 is curved preferably about the center of the opening 10 and, as noted, extends all the way from one score line 7 to the other score line 7. This score line 8 sets off the end of the tearing strip.

As shown in Figure 4, a key 11 is provided having the usual handle loop 12 and at the end of the key is a projecting member 13 which is preferably tapered toward its free end. When it is desired to open the container this projecting portion of the key is pressed against the center of the scored portion 9 and the metal ruptured along the score line 9. This will form the hole 10. The key is then inserted in the hole and, since the projection 13 thereof is of a length substantially equal to the distance between the score line 9 and the score line 8, the extreme end 14 of said projection will lie close to the score line 8 but at the left of the same as viewed in Figure 1. A rotation of the key will bring pressure to bear on the inside of the body wall adjacent the score line 8 and this will rupture the metal along the score line 8 and also to a short distance along the score line 7, thus forming the freed end of the tearing strip. The key is then removed and the slot 15 in the shank of the key is placed over the freed end of the tearing strip and, by rotating the key in the usual way, the tearing strip will be rolled onto the key and will be completely removed thus releasing the upper portion of the container from the lower portion thereof.

The body wall may also be scored along the line 16, in which case the tearing strip will be released from the body wall at this score line and there will be left between the score line 8 and the score line 16 a portion of the body wall which will serve as a hinge, permitting the upper end portion of the container to be turned to open position and again brought back to a closed position. When the body wall is scored along the line 16 the score lines 7, 7 may terminate at the score lines 8 and 16, as it is not desirable to rupture the metal between these score lines when a hinge portion is left.

The collar is provided with a bead 17 which is curved inwardly from the body wall, thus providing a space 18. This will give sufficient room for the rupturing of the metal and the forming of the hole 10 and also for the insertion of the key projection in between the collar and the body wall to a position where the score line 8 may be broken.

In Figure 1 of the drawing the collar 4, for the sake of illustration, is shown as separated from the wall of the container. This collar, however, makes firm contact with the body wall throughout. It will be noted that the bead 17 in the collar is of slightly less width than the distance between the score lines 7, 7. The metal in the tearing strip adjacent the score line 9 will be supported by the collar so that when pressure is applied to form the opening 10 by breaking the score line 8 the score lines 7, 7 will not be disturbed.

It is obvious that changes in the shaping of the parts set off by the score lines may be made without departing from the spirit of the invention set forth in the appended claim. It is, however, essential that the body wall shall be scored

so that an end of the tearing strip may be formed from the body wall and the formed end lifted so as to attach a key thereto.

I claim:

5 A sheet metal container comprising a body portion having its edges joined in a side seam, a collar disposed within said body, said body having parallel score lines setting off a tearing strip and a score line extending across the strip and setting off an end of the tearing strip, said body also being scored adjacent the end so that the body wall may be ruptured and an opening formed permitting a tool to be inserted for separating the end portion of the tearing strip from the body wall, said collar being beaded inwardly in the region of the tearing strip so as to provide a space between the collar and the body wall for the insertion of the tool, said bead being of less width than the distance between the score lines setting off the tearing strip so that the body wall at the score lines will be supported during the rupturing of the strip to form the opening for the tool.

THOMAS P. KEOGH.
